Specification for Design.

Patented Oct. 11, 1921.

Application filed June 16, 1921. Serial No. 478,173. Term of patent 3½ years.

To all whom it may concern:

Be it known that I, AMON L. LITCHFIELD, a citizen of the United States, residing at Toledo, in the county of Lucas and State of Ohio, have invented a new, original, and ornamental Design for a Radiator-Cap, of which the following is a specification, reference being had to the accompanying drawings, forming a part thereof.

In the drawing, Figure 1 is a top plan view of a radiator cap showing my new design and Fig. 2 is a front elevation thereof.

I claim:

The ornamental design for a radiator cap substantially as shown.

AMON L. LITCHFIELD.
